UNITED STATES PATENT OFFICE.

NATHANIEL P. SHELDON, OF SAN FRANCISCO, CALIFORNIA.

IMPROVEMENT IN PADDLE-WHEELS.

Specification forming part of Letters Patent No. 117,822, dated August 8, 1871.

To all whom it may concern:

Be it known that I, NATHANIEL P. SHELDON, of the city and county of San Francisco, in the State of California, have invented certain new and useful Improvements in Paddle-Wheels, of which the following is a specification:

The nature of my invention consists of a paddle-wheel so constructed that the paddle-blades will travel back and forth between the axis and periphery as the wheel revolves, the blades approaching the periphery as they enter the water and the axis as they are withdrawn, thus preventing the wheel from "backing water" and the consequent loss of power; and my invention further consists in a device for adjusting the depth to which the blades enter the water.

In the drawing, Figure 1 represents a side elevation of the paddle-wheel and the frame in which it is hung; Fig. 2, a top view of the same; Fig. 3, an end view of the same; Fig. 4, a section of the guides or ways in which the ends of the paddle-blades travel; Fig. 5, a view of the paddle-blade detached.

In Figs. 1, 2, and 3, A represents a paddle-wheel set upon the driving-shaft of a vessel and strengthened by braces E attached to its periphery and to collars D secured to the driving-shaft on each side of said wheel. The wheel A is constructed with radial arms C, forming guides or ways B, in which the paddle-blades are arranged to travel. N represents the paddle-blades, which are constructed with friction-rollers Q in the middle and O at each end, as shown in Fig. 5. The friction-rollers Q travel in the guides B when the blades are properly secured in the paddle-wheel, and the rollers O in circular guides hereinafter described. W W are ways attached

to the frame-work of the vessel on each side of the wheel A. Between these ways the circular guides or ways F are arranged, having a vertical movement therein, for the purpose hereinafter described. The said circular ways F are raised or lowered simultaneously by means of the screws H and gearing I K. The ends of the paddle-blades with friction-rollers O are arranged to travel in these ways, which are so placed as to be eccentric with the paddle-wheel, causing the blades, as the wheel revolves, to travel back and forth from the axis to the periphery of the wheel in the ways B. The ways F are so arranged that the blades will approach the periphery of the wheel as they enter the water, and recede from it as they are withdrawn. The vertical movement of the ways F in the ways W allows the depth to which the blades enter the water to be easily adjusted.

It is evident that wheels constructed according to my invention may be applied to other uses than propelling vessels; such, for instance, as water-wheels and the like.

Having described my invention, what I claim is—

1. The combination, in a paddle-wheel, of the radial arms C forming ways B, and paddle-blades N with the circular ways F, substantially as and for the purposes herein described.
2. The combination of the ways F, paddle-blades N, ways W, and screw H, as herein described.

NATHANIEL P. SHELDON.
